(57) **CLAIM**

The ornamental design for a razor cartridge, as shown and described.

DESCRIPTION

FIG. 1 is front, right, top perspective view of a first illustrated embodiment of a razor cartridge showing the new design;

FIG. 2 is a left, back, bottom perspective view thereof;

FIG. 3 is a front elevational view thereof;

FIG. 4 is a rear elevational view thereof;

FIG. 5 is a left-side elevational view thereof;

FIG. 6 is a right-side elevational view thereof;

FIG. 7 is a bottom plan view thereof; and,

FIG. 8 is a top plan view thereof.

The broken lines illustrate portions of the razor cartridge that form no part of the claimed design.

1 Claim, 3 Drawing Sheets
